UNITED STATES PATENT OFFICE

140,956

DESIGN FOR A DOLL

William Seidler, New York, N. Y.

Application February 2, 1945, Serial No. 117,730

Term of patent 3½ years

(Cl. D34—4)

To all whom it may concern:

Be it known that I, William Seidler, a citizen of no country, and resident of New York city, in the county of New York and State of New York, have invented a new, original, and ornamental Design for a Doll, of which the following is a specification, reference being had to the accompanying drawing, forming a part thereof, and of which

Fig. 1 is a view in front elevation showing my new design; and Fig. 2 is a side view thereof.

Both front and back of the doll are identical in appearance.

I claim:

The ornamental design for a doll, substantially as shown and described.

WILLIAM SEIDLER.
